UNITED STATES PATENT OFFICE.

WILLIAM RECKE, OF NEW YORK, N. Y.

ELECTRIC SIGN.

1,203,049.

Specification of Letters Patent. Patented Oct. 31, 1916.

Application filed June 5, 1914. Serial No. 843,267.

To all whom it may concern:

Be it known that I, WILLIAM RECKE, a subject of the Czar of Russia, and residing at New York, in the county of New York and State of New York, have invented certain new and useful Improvements in Electric Signs, of which the following is a specification, such as will enable those skilled in the art to which it appertains to make and 10 use the same.

This invention relates to electric signs or display apparatus, and the object thereof is to provide an apparatus of this class which is so constructed as to produce a moving 15 picture or moving pictures similar to those produced by the cinematograph; a further object being to produce shade effects in said pictures; and with these and other objects in view the invention consists in an apparatus of the class specified, constructed and 20 operating as hereinafter described and claimed.

The illusion of a moving picture as produced by the cinematograph requires extremely rapid changes of pictures, which are possible in that moving picture machine because the pictures to be changed require space less than an inch square each, and are carried by a substance of insignificant 30 weight and minute thickness. But to change pictures contained by a sheet of metal or paper in the same manner would be quite a different proposition, especially when the fact is considered that it takes a 35 field of thousands of lamps to produce even the simplest design in relief line arrangement distinguishably. Were the lamp circuits to terminate at the said sheet the resulting heavy wires and heavy insulation 40 required by safety regulations would demand a terminal plate many inches square, which distance would have to be jumped by the sheet at each change of pictures. And were the plate to make the jumps thus permitting a smooth travel of the sheet, the 45 proposition would hardly be less difficult on account of the weight of the jumping parts. Moreover, in either case would the illumination be interrupted between the changes to 50 an extent as to render the resulting moving picture indistinct, if not invisible. The arrangement of the terminals in squares is, however, essential as it is impossible to place them all in a single row or in a few 55 rows practically.

The present invention overcomes all the

above named obstacles in a simple and practical manner.

The invention is fully disclosed in the following specifications, of which the accompanying drawings form a part, in which the separate parts of my improvement are designated by suitable reference characters in each of the views, and in which: Figure 1 is a sectional side view of an apparatus 60 involving my invention and on the line 1—1 of Fig. 2; Fig. 2 a section on the line 2—2 of Fig. 1; Fig. 3 a section on the line 3—3 of Fig. 2; Fig. 4 a partial section on the line 4—4 of Fig. 2; Fig. 5 a view looking in the 65 direction of the arrow 5 of Fig. 2 and showing only part of the construction; Figs. 6 and 7 are sectional views of contact devices or flashers which I employ; Fig. 8 a length of a film which I employ; Figs. 9, 9^a, 9^b, 9^c 70 and 9^d are views of parts of the film showing different ways of marking the same; Fig. 10 a plan view of an electrical display sign; Fig. 11 a plan view of a magnet supporting board; Fig. 12 a plan view of a 75 contact supporting board; Fig. 13 a detail sectional view of an improved magnet which I employ; Fig. 14 a diagrammatic view showing the electrical operation of the various parts of my invention; Fig. 15 a 80 view similar to Fig. 14 but showing only a part of the construction shown in said figure and showing a modification; Fig. 16 a view similar to Fig. 1 but omitting the various parts of the construction and showing a modification; Fig. 17 a section on the 85 line 17—17 of Fig. 16; Fig. 18 an enlarged section on the line 18—18 of Fig. 16; Fig. 19 a section on the line 19—19 of Fig. 18; Fig. 20 a view similar to Fig. 16 but showing only a part of the construction and 90 showing the same in section; Fig. 21 a diagrammatic view of the circuit employed in connection with the construction shown in Figs. 16 to 19 inclusive; Fig. 22 a view similar to Fig. 14 but showing a modification; Fig. 23 a view combining Figs. 14, 16 and 22 and showing additional features of construction for producing shade effects; Fig. 24 a view similar to Fig. 10 and indicating 95 the production of shade effects.

In Figs. 1 to 14 inclusive, I have shown a simple form of my construction and in Figs. 1 to 5 I have shown the operative mechanism and in said last named figures, 100 I have shown at *a* the frame of the operative mechanism, said frame being composed

of vertical side members connected at the top as shown at a^2 , and at the bottom by a cross bar a^3 . Pivoted within the frame a and to the top a^2 as shown at a^4 is a tubular 5 arm a^5 provided adjacent to its lower end with an adjustable contact plate a^6 in which is mounted a plurality of contacts a^7 with which are connected a corresponding number of wires a^8 . Secured to the lower end 10 of said tubular arm a^5 is a block provided with a downwardly directed arm a^9 with the lower end of which is rotatably connected a roller a^{10} . Mounted between the contact plate a^6 and the said block is a 15 vertically movable plate b provided at each side with projecting arms b^2 with which are adjustably connected operating rods b^3 and b^4 , and the rods b^3 are connected with one end of a long rock bar b^5 pivoted centrally of the top of the frame a at b^6 . The 20 rods b^4 are connected with one end of a short rock bar b^7 pivoted at one side of the top of the frame as shown at b^8 .

Secured to the top of the vertically movable plate b is a flexible pad b^9 , and adjustably connected with the long rock bar b^5 is a rod b^{10} , and adjustably connected with the short rock bar b^7 is a rod b^{11} .

Rotatably mounted in the frame a is a 30 main shaft c on one end of which is secured a pulley around which is passed a belt c^2 which is also passed around a pulley on the shaft of a motor c^3 , and secured centrally of said shaft is a grooved cam wheel c^4 adapted to rotate with said shaft, and the roller a^{10} of the arm a^9 is adapted to operate in the groove of the said cam wheel c^4 , or be operated thereby when the same rotates, and this operation will oscillate the tubular arm a^5 as will be understood. Secured to the 35 shaft c are three contact blocks or flashers c^5 , c^6 and c^7 having metal faces c^8 , and secured to the bar a^3 at the bottom of the frame are brushes c^9 arranged in pairs, each 40 pair operating in connection with the flashers c^5 , c^6 and c^7 . The flasher c^6 is shown in Fig. 7, and Fig. 6 shows the flasher c^7 which is similar to the flasher c^5 . The end 45 of the shaft c with which the belt c^2 is connected is provided with a cam block c^{10} which operates in connection with a roller c^{11} secured to an arm c^{12} pivoted to the frame at c^{13} , and the rods b^{10} and b^{11} are connected with the free end of said arm c^{12} . 50 as clearly shown in Fig. 4, and by means of this construction the plate b receives its vertical movement at each revolution of the shaft c . The other end of the shaft c is provided with a pinion c^{14} , and mounted 55 above and at one side of the shaft c is a supplemental shaft d on one end of which is secured a gear d^2 which meshes with a gear d^3 secured to a stub shaft d^4 mounted below the shaft c , and on which is also 60 mounted another gear d^5 which meshes with 65

the pinion or small gear c^{14} of the shaft c , and by means of this gearing the shaft c rotates six times to one rotation of the shaft d .

Mounted on the shaft d centrally thereof 70 is a wide film wheel d^6 provided adjacent to its ends with a plurality of teeth or projections d^7 , and in the construction shown, I provide a plurality of guide rollers d^8 , the arrangement of which is clearly shown in Fig. 1, and passed around the film wheel d^6 and the guide rollers d^8 is an endless film 75 d^9 preferably composed of sheet metal, and the side edges of which are provided with apertures d^{10} in which the teeth or projections d^7 of the wheel d^6 operate.

In Fig. 9 of the drawing, I have shown the film provided with projections e . In Fig. 9^a, I have shown the film provided with raised lines e^2 . In Fig. 9^b said film is provided with apertures e^3 . In Fig. 9^c I have shown a sketch or drawing e^4 on the film, which I prefer to the apertures e^3 , as the exact relations between the film d^9 and the contacts a^7 , hereinbefore mentioned, are not essential to the sketch e^4 , nor to the projections e , it being understood that when a line or projection will not touch the contact designated for it, it will touch the next contact thus shifting the whole picture one 90 lamp, provided the contacts are arranged exactly like the lamps, as shown in Figs. 10 and 12, and the markings, in case of a relief line picture, are arranged in exactly the form to be produced on the display device 95 f . In Fig. 9^d I have shown a modification of the arrangement of matter or markings on said film which consists in dividing said film centrally as indicated by the dotted line e^5 and placing one-half of said matter or markings on each side of said line, as shown at e^6 . This will shorten the length of the film and may add to its width and the only essential change to produce the same properly on a sign will be to correspondingly arrange the wires a^8 of the contacts a^7 . This form will be employed mostly in connection with the apertures e^3 and is not ordinarily adopted for the other ways of marking the 100 film as the parting line will appear on the device f unless exact relations between film and contacts are maintained which it is impossible to do when continuous lines, shown in Figs. 9^a and 9^c, are contained by the film d^9 . In all of the above named ways of marking the film d^9 , it will be understood 105 that the same may be arranged in any desired manner, and when one style of marking is selected for producing a particular moving picture on a film the same will be used throughout its length except where other subject-matter than said particular moving picture is desired. A short length of the film d^9 so marked is shown in Fig. 8. At d^{11} the letter N is represented and at d^{12} 110 115 120 125 130

the said letter begins to gradually change its size as well as its position on the film d^9 and at the same time gradually loses its equilibrium until at d^{13} the letter Z is formed. For simplicity's sake I have shown a letter in this figure, but it will be understood that an endless variety of design, motion and shading may be produced by means of this film, the only material difference between 10 my film and the film employed in connection with the cinematograph, also known as "the moving picture machine", being that while the latter selects rays of light, the film d^9 selects electric circuits. In all cases of marking the film d^9 a coat of liquid insulation is applied to the surface of the film, except when apertures are employed, as shown in Fig. 9^b, and in the construction shown in Fig. 9^c the sketch may be made by scratching off the said liquid insulation when dry.

Mounted beneath and in connection with the film d^9 and between the wheel d^6 and the tubular arm a^5 is a contact brush e^7 with which is connected a wire e^8 . The contact plate a^6 may be adjusted in the arm a^5 with respect to the film d^9 by means of screws or bolts e^9 which are passed through elongated slots e^{10} in the opposite sides of said arm to obtain exact relations between the said plate 25 and definite parts of the film d^9 the relative position of which is fixed by the gear mechanism shown in Figs. 1, 2 and 5, which propels it.

In Fig. 14 of the drawing, I have shown 30 a diagrammatic view of the electric circuits, and have indicated the operation of my complete apparatus in a simple form, and in said figure I have shown at f an electrical display device provided with a plurality of 35 lamps f^2 , and at f^3 I have shown a corresponding number of magnets, and at f^4 the contact plate a^6 having a corresponding number of contacts. The magnets which I employ are particularly designed for use 40 with my construction in order to produce the best results, and consist of a coil f^5 through which passes the usual core f^6 having a pole piece f^7 to which is secured a yoke-shaped frame f^8 , and secured to the core f^6 is the usual armature arm f^9 , and secured to the frame f^8 is a binding screw f^{10} and an adjusting screw f^{11} , and secured to but insulated from the core f^6 is a spring contact f^{12} , and secured to but insulated 45 from a metal board f^{13} to which the magnets are secured is a sheet metal facing f^{14} with which said spring contact f^{12} engage. In Fig. 14, I have also shown the shaft c and the flashers c^5 , c^6 and c^7 thereon, and 50 the brushes c^9 in contact therewith, and also the film d^9 and film wheel d^6 , and in said figure I have shown the film d^9 provided with three projections e similar to those shown in Fig. 9, in contact with a plurality 55 of contacts a^7 and the wires a^8 of said con-

tacts are connected to the binding screws f^{10} of a corresponding number of magnets to which are connected other wires g which are wound on said magnets to form coils f^5 , and the other ends of said wires are secured to the spring contacts f^{12} as shown at g^2 . Connected with the metal board f^{13} is a wire g^3 which is connected with one of the brushes c^9 of the flasher c^7 , and connected with the other brush of said flasher 70 is a wire g^4 which also connects with one brush c^9 of the flasher c^5 as shown at g^5 , and with one brush c^9 of the flasher c^6 as shown at g^6 , and in said line or wire is placed a battery g^7 . The sheet metal facing 75 f^{14} is also provided with a wire g^8 which is connected with the wire g^4 , as clearly shown, and connected with the binding screws f^{10} of the magnets are other wires g^9 which are connected with the lamps f^2 , and another 80 wire g^{10} is connected with the lamps f^2 and with one brush of the flasher c^5 as shown at g^{11} , and the wire g^8 connected with the brush e^7 is connected with one brush of the flasher c^6 . The above wiring completes the 85 circuits through the magnets, lamps, contact pieces, film and battery, and are governed by the arrangement of the metal facing c^8 on the flashers c^5 , c^6 and c^7 , and by tracing these circuits it will be found that when the 90 projections e on the film d^9 make contact with the contacts a^7 , the circuit through the magnets is first completed by the flasher c^6 , and said magnets close the circuits to the 95 lamps by the flashers c^5 and c^7 , and by 100 means of the flashers and magnets the lamps will remain illuminated during almost a complete revolution of the flashers, although the contact between the projections e of the film d^9 and contacts a^7 is broken, 105 and immediately after the lamps go out the next series of projections will have advanced due to the rotation of the film wheel d^6 , and the said series will make contact with the contacts a^7 and the lamps f^2 will be 110 again illuminated. As above described in the operation of the arm a^5 which swings in the direction of the arrow x of Fig. 1, said arm travels at the same speed as, and with, the film and returns to the position 115 shown in Fig. 1 by means of the grooved cam c^4 . The construction of the groove of the cam c^4 is such as to cause the contacts a^7 in the arm a^5 to move with the film during a small part only of the revolution of 120 the shaft c thus giving the arm a^5 sufficient time to return without abrupt stops or jerks.

The wires a^8 in the arm a^5 are necessarily 125 very thin and light to present a minimum incumbrance to the oscillations of the arm and flasher c^7 is interpolated between the battery g^7 and the wire g^{10} to prevent an overload in the wires a^8 after the flasher c^6 has closed its circuit and before flasher c^7 130

closes its circuits, at which time the lamp circuits would also be closed, across the wires g^9 , the wires a^8 , the film d^9 , the flasher c^6 , the battery g^7 and the wire g^{10} , in the absence of the flasher c^5 . As the flashers c^5 , c^6 and c^7 close and open the circuits there is absolutely no sparking at the contacts a^7 and the contacts of the magnets between the armature f^9 and the frame f^8 . The shaft c revolves at high speed and as the conducting facing c^8 of the flashers c^5 and c^7 embraces nearly the whole circumference of the said flashers, the illumination of the display board f will appear to be continuous.

15 The operation is as follows:—The endless film d^9 is moving continuously in the direction of the arrow x^2 , and by means of the grooved cam c^4 the tubular arm a^5 is given at predetermined intervals a movement in 20 the same direction and at the same speed as the film and the plate b presses the film against the plate a^6 at which time a series of lamps will become illuminated and will continue to be so by means of the magnets 25 and flashers hereinbefore described and, as will be readily understood, a moving picture or pictures similar to those produced by the hereinbefore mentioned moving picture machine may therefore be produced on the electrical display device f .

In Fig. 15, I have shown a modification to be used when the apertures e^3 in the film d^9 are employed instead of the projections e and in place of the vertically movable plate b I employ a vertically movable box-shaped member h in which are mounted a plurality of spring-operated pins h^2 , the number of which will correspond with the number of contacts a^7 , and it will be understood that 40 when said box-shaped member h is in the position indicated by dotted lines in said figure, the end of the pins h^2 will not engage the film d^9 , but when in the full position, the pins h^2 either engage the film or pass 45 through the apertures e^3 therein and make contact with the contacts a^7 as clearly shown, and in this construction the wire e^8 is connected with the box member h and not with the film, and the operation of the parts of 50 the operating mechanism will be the same as that of the construction shown in Figs. 1, 2 and 14.

The pad b^9 , also shown as a brush in Figs. 16, 22 and 23, owing to the minute thickness 55 of the film d^9 forces each of the projections e , the raised lines e^2 or the scratched off portions e^4 , whichever case it may be, independently of each other against the contacts facing them. In case of apertures e^3 the 60 independently yielding elements are the pins h^2 , described above, the object in either case being to insure uniform contact between the opposing contact surfaces by rendering at least one of them resilient.

65 The reason for employing the flashers

c^5 , c^6 and c^7 or like devices is to prevent the sparking at the contacts, and the magnets as well as to provide means for governing the opening and closing of the circuits.

In the construction shown in Figs. 1 and 2 70 the endless film d^9 is passed around the film wheel d^6 and around four guide wheels d^8 , as clearly shown, and in this construction only a short film can be used practically as the lengthening of the same would necessitate the addition of other guide wheels d^8 which would take up considerable space if a film of five hundred or one thousand foot were used. It is therefore necessary and 75 essential to employ a mechanism which will enable me to use an endless film of any length with my construction.

In Figs. 16 to 21 inclusive, I have shown a simple compact reel mechanism for producing the desired result above referred to, 80 and in Fig. 16, I have indicated the location of the contact plate a^6 having the contacts a^7 and the vertically movable plate b as well as the film wheel d^6 and three guide wheels d^8 , and mounted in the frame a 85 which supports the various parts above referred to is a tubular shaft i on which is loosely mounted a bar i^2 in opposite ends of which are mounted shafts i^3 on the outer ends of which are rotatably mounted reels i^4 and i^5 . Rotatably mounted on the tubular shaft i between the frame member a and the bar i^2 is a gear or toothed wheel i^6 having a hub portion provided with a groove i^7 in which is placed a belt i^8 which is also passed 90 around a pulley j secured to a shaft j^2 supported in the frame member a , and secured to the shaft j^2 adjacent to the pulley j is another pulley j^3 around which is passed another belt j^4 which is also passed around a 95 motor pulley not shown. Secured to the outer end of the tubular shaft i is a friction wheel k having a sheet metal facing k^2 , and secured to the shaft i between the wheel k and the bar i^2 is a contact block k^3 having 100 an insulating spot k^9 on opposite sides of the said block, and supported by the bar i^2 as shown at k^4 are three brushes k^5 , k^6 and k^7 . The brushes k^5 , and k^6 are adapted to engage the contact block k^3 while the brush 105 k^7 engages the shaft i as clearly shown in Fig. 21. Supported in the bar i^2 is a magnet m , and pivoted to said bar adjacent to said magnet is an armature arm m^2 having a spring m^3 adapted to normally hold the 110 same in connection with stops m^4 secured to the frame member a as clearly shown in Fig. 17, and secured to the bar i^2 at m^5 is a brush m^6 adapted to engage a metal ring m^7 secured to the friction wheel k and having an 115 electrical connection with the sheet metal facing k^2 thereof as shown at m^8 in Fig. 21. The reels i^4 and i^5 are exactly alike and consist of a central hub portion n approximately semi-spherical in cross section, as 120

clearly shown in Fig. 20, and circular side plate members n^2 which form guides for the film d^9 when wound thereon, and said side plate members n^2 are provided with circular apertures n^3 . Pivoted to the outer side of said reel as shown at n^4 is a plate n^5 having at one end a circular head n^6 which is adapted to operate in one of said apertures n^3 and the other end of said plate n^5 is provided 10 with a smaller head n^7 . Pivoted in the side edge portions of the plate n^5 adjacent to the head n^7 are operating rods n^8 which pass through and operate in apertures n^9 in the hub portion n of the reel and are connected 15 with a plate n^{10} pivoted to the back of the reel as shown at n^{11} , and said plate n^{10} is also provided with a circular head n^{12} similar to the head n^6 of the plate n^5 . The heads n^6 and n^{12} of the plates n^5 and n^{10} extend 20 inwardly to form circular members around which the film passes as hereinafter described. One corner of the semi-circular hub portion n is provided with a recess n^{13} in which is pivoted an L-shaped contact device o , the head o^2 of which is adapted to engage the sheet metal facing k^2 on the wheel k , and said device o is held in engagement with said facing by means of a spring o^3 , as clearly shown in Fig. 19. The back 25 of the reel is also provided with a circular flange or rim n^{14} , and mounted on the shaft j^2 is a friction wheel n^{15} adapted to engage said rim portion and rotate said reel in the 30 operation of the apparatus, as clearly shown 35 in Fig. 17.

Mounted adjacent to and above the reels i^4 and i^5 is an oblong guide frame o^4 , the lower surface of which is cut out as shown at o^5 to form guide grooves o^6 clearly shown 40 in dotted lines in Fig. 16, and the heads n^7 of the plates n^5 are adapted to operate in connection with said frame o^4 , or the grooves o^6 therein. Secured to the back of the hub portion of the reels i^4 and i^5 and 45 within the rim portion n^{14} are brushes o^7 and o^8 which bear on the shafts i^3 , and connected with said brushes and the L-shaped devices o are wires p and p^2 , and connected with the brush m^6 is a wire p^3 which is 50 coiled around the magnet m , and connected to the brush k^7 by a wire p^4 , and secured to the shaft i is a wire p^5 which is connected with a battery p^6 , and a wire p^7 is 55 connected with said battery and with the contact block k^3 , and connected with the brush k^5 is a wire p^8 which is also connected with both the shafts i^3 , and connected with the brush k^6 is a wire p^9 which is 60 connected to a contact p^{10} adapted to engage the armature arm m^2 and another contact p^{11} which also engages said armature arm is provided with a wire p^{12} which is 65 connected with the wire p^3 . The above wiring is clearly shown in Fig. 21 and the object thereof is to govern the winding and un-

winding of the film on the reels i^4 and i^5 and, in Fig. 20, I have indicated the direction of travel of the film and if considered in connection with Fig. 16, it will be seen that the reels i^4 and i^5 have changed their position by reason of the fact that the film on the reel i^5 had been completely unwound and the L-shaped device o freed so as to make contact with the metal facing k^2 , and this contact completes the circuit through the 70 wires to the battery and magnets. This draws the armature arm m^2 in engagement with the gear or toothed wheel i^6 and is held there, circuit having been completed across the contacts p^{10} and p^{11} until the circuit is 80 broken and the gear i^6 which is continually rotating will carry with it the arm i^2 which supports the reels i^4 and i^5 .

In the above operation of rotating the bar i^2 with its connected parts the head n^7 of 85 the reel i^5 engages the guide frame o^4 , or the grooves o^6 therein and this depresses the plate n^5 on said reel which depression projects the circular heads n^6 and n^{12} as indicated in dotted lines in Fig. 18, and this permits the free passage of the film d^9 , and by 90 means of the construction of the grooves in the guide frame o^4 , the heads n^6 and n^{12} will remain projected until the film has again passed between said heads after which the 95 same retain the position shown in Fig. 18. The bar i^2 will continue its semirevolution until brush k^6 has reached the insulated spot k^9 on the block k^3 . The rotation of the bar i^2 will now have been stopped due to the 100 breaking of the circuit in the wires p^9 and p^{12} connected to the contacts p^{10} and p^{11} . The reel i^5 will now be rotated by means of the friction wheel n^{15} and the film in the beginning of this operation will assume the 105 position shown in Fig. 20, in which position the film is passed around the heads n^6 and n^{12} of the reel i^5 and about to be wound thereon, and in this position or in the beginning of the winding, the L-shaped arm o 110 has been forced inwardly by said film and the head o^2 thereof clears the facing k^2 . In the above operation of winding or unwinding the endless film, the same is continuously traveling in one direction and by 115 means of the spring-operated rollers r shown in Fig. 16, any number of which may be employed, any slack in the film can be avoided, and it will be understood that at predetermined intervals governed by the 120 length of the film the reels i^4 and i^5 change their position and during this changing as well as after the same the wheel k prevents the too free turning of the reel.

The construction shown in Figs. 16 to 21 125 inclusive, is, of course, practical and to a great advantage with my construction as well as with any other construction of a similar class with which the same may be used practically. But the winding device is sub- 130

ject to a separate application for Letters Patent, and I do not claim it herein except in combination.

- The construction shown in Fig. 22 is the same in all respects as that shown in Fig. 14, except that I provide a supplemental contact board *s* having a plurality of contacts corresponding with the contacts on the contact plate *a*⁶, and connected with the wires *a*⁸ which are connected with the contacts *a*⁷ are branch wires *s*² connected with the contacts on the board *s*, and connected with the wire *g*¹⁰ is a branch wire *s*³, and connected with the wire *g*⁴ at *s*⁴ is a branch wire *s*⁵.
 15 Connected with an electrical pencil *s*⁶ is a wire *s*⁷ which is also connected with the wire *g*³, and connected with the wire *s*⁷ is a branch wire having a contact *s*⁸, and connected to the ends of the wires *s*⁹ which correspond 20 with the wire *g*⁴ in Fig. 14 are contacts *s*¹⁰, and mounted adjacent to the contacts *s*⁸ and *s*¹⁰ is a switch arm *s*¹¹ adapted to engage the same, and mounted in the branch wires *s*³ and *s*⁵ is another switch arm *s*¹². In the 25 position of the switch arms *s*¹¹ and *s*¹² shown in full lines, the circuits through the wires to the flashers and contacts in the contact plate *a*⁶ are broken and the pencil *s*⁶ may be drawn over the contact board *s* in any manner to produce script or sketch work, and the contacts touched by the pencil *s*⁶ will illuminate a corresponding lamp on the display board *f*, as will be readily understood, and the same will remain illuminated by means 30 of the magnets until the switch arms *s*¹¹ and *s*¹² are thrown into their dotted line position shown in Fig. 22, in which position moving pictures can be produced on said display board in the hereinbefore described 35 manner, to wit: by causing the contacts *a*⁷ to engage continuously new blocks of the film *d*⁹ at exceedingly brief intervals, which engagement will transmit current from or through the said film to a number of the said contacts selected by the markings of the film and thus cause continuously new sets of the lamps *f*² to light up in such order as to produce the illusion of a moving object on the display board *f*, provided the film *d*⁹ has 40 been so marked. Although this construction is not capable of the production on the device *f* of motion sufficient to be properly classed among that of moving pictures of the scope hereinbefore described and hereinafter claimed, it being limited to the lengthening and multiplication of lines, this attachment will work to a great advantage at election time for example. The herein 45 described moving pictures may be produced and at any desired moment the returns may also be produced along with sketches and the like. It will be understood that the switch arms *s*¹¹ and *s*¹² must be manipulated in changing from one production to another except when the shaft is idle and in the 50 55 60 65

position shown in Fig. 14, at which time script or sketch work can be produced with the switches *s*¹¹ and *s*¹² remaining in their dotted position, as the flashers will not now break the circuits and the lamps caused to light up by the action of the pencil *s*⁶ will remain lighted until the desired script or sketch is completed.

In the construction shown in Figs. 23 and 24, I have shown means for producing tone or shade effects in a moving picture or moving pictures, which consists simply in the addition of complete sets of magnets and contacts corresponding to the first set as well as complete films. In Fig. 23, I have indicated the lamps *f*², flashers *c*⁵, *c*⁶ and *c*⁷ and the contacts *a*⁷, and the magnets of the first set, but in said figure I have shown a simple form of magnet *t*, comprising a core *t*² with the ends of which engage armature arms *t*³ and *t*⁴, and connected to the armature arm *t*³ is a wire *t*⁵ which is connected with a battery *t*⁶, and a wire *t*⁷ is connected with said battery and a brush engaging the flasher *c*⁵, and connected with another brush engaging said flasher is a wire *t*⁸ which is also connected with the lamp or a plurality of lamps *f*², and connected with said lamp is a wire *t*⁹ the end of which is provided with a contact *t*¹⁰ adapted to engage the armature arm *t*³. At *u* I have shown another battery and connected therewith is a wire *u*² which is coiled around the magnet *t*, and is connected with the contact *a*⁷ by the wire *u*³, a branch of which is provided with a contact *u*⁴, adapted to engage the armature arm *t*⁴, and connected with the battery *u* is another wire *s*⁷ a branch of which is connected with the switch arm *s*¹¹ and connected with the switch contacts *s*¹⁰ are the wires *s*⁹ one of which is also connected with one brush of the flasher *c*⁷, and connected with the other brush of said flasher is a wire *u*⁶ which is connected with the armature arm *t*⁴ and the other wire *s*⁹ is connected with one brush of the flasher *c*⁶ and the other brush of said flasher is provided with a wire *u*⁸ which is connected with the film.

The above wiring completes the circuit of one complete apparatus similar to that shown in Fig. 14 providing the switch arms *s*¹¹ and *s*¹² are in their dotted position, and to produce said tone or shade effects I simply add to the wire *t*⁹ a branch in which I place a resistance coil *v*, and attach a branch wire to the wires *u*², *u*⁶, *u*⁸ and *t*⁵, and another magnet *t*, contact *a*⁷ and film *d*⁹, and it will be understood that the greater number of these branches the greater number of shade effects will be produced, and in Figs. 23 and 24, I have shown a construction adapted to produce three shades, as clearly indicated in Fig. 24. In said figure I have shown three series of lamps *w*, *w*² and *w*³, and it will be understood that the lamps *w*

will be illuminated by the first complete apparatus, while the lamps w^2 and w^3 are illuminated by the second and third apparatus, or as shown in Fig. 23, all being governed by the same flashers. In short, the production of tone or shade effects on a display device is accomplished by the addition of a film corresponding with the film of the main apparatus, a corresponding number of magnets and a corresponding number of contacts and a resistance coil. The function performed by the flasher c^5 in this construction is the closing and opening of the lamp circuits which in this instance are separated from the magnetic circuits. In Fig. 23 I have shown also the means for producing script, including the pencil s^6 connected with the battery u by the wire s^7 , the contact s^{14} connected with the wire u^3 by the branch wire s^2 , the switch arm s^{12} connected with the wires t^7 and t^8 by the branch wires s^5 and s^8 , and the switch arm s^{11} also connected with the wire s^7 and leading to one brush of each of the flashers c^6 and c^7 as described above, across its contacts s^{10} and the wires s^9 . In addition, I have shown in that figure the endless film passed around the film wheel d^6 , around the guide wheels d^8 , and the reel mechanism comprising the reels i^4 and i^5 with their respective plates n^5 the heads n^7 of which are adapted to engage the frame o^4 , the toothed wheel i^6 , the friction wheel k and the driving friction wheel n^{15} . Although the film-controlled part of my apparatus is particularly adapted for the production of moving pictures, a series of fixed pictures or other advertising matter may be flashed on the display board by placing a different design on each block of the film and by revolving the main shaft slowly or intermittently, as will be understood. Fixed pictures or the like may also be produced with the said shaft revolving at full speed by simply providing successive blocks of the film with one and the same design. Script work may also be produced by the film-controlled apparatus in the very same manner as the ordinary moving picture machine performs that feature.

It will be understood that the contacts on the contact plate or contact board are very small as are also the markings of the film, and in Figs. 2 and 3, I have tried to indicate their proportionate size, and while I have shown the apparatus as driven by motor power, it will be understood that the same may be turned by hand, if desired, by employing a crank which is not shown.

Although I have shown and described one form of apparatus to produce a moving picture or moving pictures with shade effects and script or sketch work on a display board, it will be understood that the same may be constructed along the same lines as

an ordinary moving picture machine employing a film adapted to be wound and rewound, or the said apparatus may be constructed in any desired manner within the scope of the appended claims.

Having fully described my invention, what I claim as new and desire to secure by Letters Patent, is:—

1. An apparatus of the class described involving means for producing pictures on a display surface and means for simultaneously producing script or sketch work on said display surface.

2. The combination of a display board, a plurality of current receiving devices, a plurality of contacts, a circuit selector moving in one direction, and means for engaging said selector with said contacts during its movement in said direction to admit electric current to a selection from among said contacts for energizing said devices so as to produce a picture on said board, with means for holding said picture or the like on said board.

3. In an electric display apparatus, a plurality of current receiving devices, a conducting circuit selector having insulating parts, a yielding conducting member engaging said selector on one side, a conducting member engaging said selector on the opposing side, means for transmitting current through or across the conducting parts of said selector from one of said members to the other for energizing a selection from among said devices and means excluding said members for sustaining the energization of said devices.

4. In an electric display apparatus, a pair of plates reciprocating together and a circuit selector passing between and in the direction of the reciprocations of said plates.

5. In an electric display apparatus, a traveling circuit selector and a plurality of contacts separate therefrom and arranged to travel with said selector.

6. In an electric display apparatus, a reciprocating conducting surface, a conducting surface formed by a plurality of resilient elements in circuit, and reciprocating with said first named surface and a circuit selector passing between, and in the direction of the reciprocations of, said surfaces.

7. In an apparatus of the class described, a plurality of reciprocating contacts and a circuit selector traveling in the direction of the reciprocations of said contacts.

8. In an electric display apparatus, a plurality of circuits, reciprocating terminals for said circuits and a member engaging said terminals for selecting said circuits during the reciprocation of said terminals.

9. In an electric display apparatus, a plurality of magnets, a plurality of contacts, means for admitting current to a selection from among said contacts to energize a se-

lection from among said magnets and means for preventing sparking at said contacts and said magnets.

10. In an electric display apparatus, means controlled by an endless tape for producing a picture or the like with shade effects, on a display surface, means for winding said tape, and means for producing script or sketch work on said board.

11. The combination of a plurality of current receiving devices, and a reciprocating contact plate having a plurality of contacts, with a circuit selector passed around a plurality of wheels and admitting electric current to successive selections from among said contacts to energize said devices.

12. The combination of a display board, a plurality of indicators, and a contact plate having a plurality of contacts, with a series of circuit selectors passed around a plurality of wheels and moving in one direction, and means for engaging constantly new selectors from among said series with said contacts during the movement in said direction of said series to produce contrast among said indicators in such manner that script or sketch work under process of construction will be produced on said board.

13. The combination of a display board, a group of indicators, and a plurality of magnets, with means for energizing a selection from said magnets to operate said indicators so as to produce a picture on said board with shade effects in said picture.

14. The combination of a display board, a plurality of current receiving devices, a plurality of contacts and a series of circuit selectors, with means for engaging constantly new selectors from among said series with said contacts so as to admit current to successive selections from among said contacts, and energize said devices so as to produce a picture gradually changing its design, on said board.

15. The combination of a plurality of indicators, with a plurality of contacts, a circuit selector traveling in one direction and engaging said contacts to admit current during its travel in said direction to such contacts as will change the appearance of a sufficient number of said indicators for representing a picture by their change, and means for preventing sparking at said contacts.

16. In an electric display apparatus, a plurality of circuits, reciprocating terminals for said circuits, means for admitting current to a selection from among said circuits during the reciprocation of said terminals.

17. In an electric display apparatus, a plate reciprocating in cross directions.

18. In an apparatus of the class described, a plate describing a circle.

19. The combination of a display surface formed by a plurality of alike parts, with a plurality of electromagnets, at least one for

each of said parts, means for energizing a number of said electromagnets to close circuits, said closing causing the production of temporary contrast among said parts, said contrast producing a picture, and means for preventing all sparking at said electromagnets.

20. The combination of a display surface formed by a plurality of similar parts, with a plurality of magnets, a plurality of contacts, at least one for each of said parts, means for admitting current to a number of said contacts to energize said magnets for closing circuits, said closing actuating a stronger current for causing a temporary production of contrast among said parts, said contrast producing a picture, and means for preventing all sparking at said contacts.

21. In an electric display apparatus, means for producing pictures with shade effects on a display surface and manual means for producing script or sketch work on said surface.

22. The combination of a plurality of indicators, with means for producing contrast among said indicators, said contrast producing a half tone picture.

23. In an electric display apparatus, a pair of reciprocating plates and a circuit selector adapted to pass between said plates.

24. The combination of a display surface formed by a plurality of alike parts, with a plurality of magnets, at least one for each of said parts, a plurality of contacts, automatic means for admitting current to said contacts to energize said magnets, said energization producing contrast among said parts, said contrast producing a picture, and means including said magnets but excluding said contacts for prolonging said contrast.

25. The combination of a plurality of indicators, with a contact surface formed by a group of contacts, automatic means for admitting current to a part of said surface to produce contrast among said indicators, said contrast producing a picture, and means excluding said contacts for prolonging said picture.

26. The combination of a plurality of indicators, with a film adapted to be passed around a plurality of wheels, means controlled by said film for producing contrast among said indicators, said contrast producing a picture, and means excluding said film for prolonging said contrast.

27. The combination of a plurality of indicators, with a plurality of contacts, and a series of circuit selectors each admitting current to a number of said contacts, said current actuating a stronger current for producing contrast among said indicators, said contrast producing a picture.

28. The combination of a plurality of indicators, with a plurality of contacts, and a series of moving circuit selectors forming a procession and admitting current during said

movement to such of said contacts as will produce contrast among said indicators and thereby produce an image of an object various parts of which move in various directions.

29. The combination of a plurality of indicators with a traveling film and means controlled by said film during its travel for producing contrast among said indicators, said 10 contrast producing a picture moving in various directions.

30. An apparatus of the class described,

involving electric means for producing pictures on a display surface and manually operated electric means for producing script or 15 sketch work on said surface.

In testimony that I claim the foregoing as my invention I have signed my name in presence of the subscribing witnesses this 3rd day of June, 1914.

WILLIAM RECKE.
